METHOD OF PROMOTING DIURESIS

Anangur V. Subbaratnam, Chicago, Ill., assignor to
Wilson & Co., Inc., a corporation of Delaware
No Drawing. Filed Apr. 7, 1964, Ser. No. 358,064
4 Claims. (Cl. 167—65)

This invention relates to therapeutic agents. More particularly, it relates to the compounds which are highly effective as diuretic agents. Still more particularly, the invention relates to a method of inducing or promoting a high rate of urine flow and electrolyte excretion by administration of pharmacologically active dosages of compounds falling in the category of derivatives of cinnamic acid.

In accordance with the present invention a compound or mixture of compounds selected from the class identifiable generally as substituted cinnamic acids and the water-soluble salts formed by the use of pharmacologically acceptable cations, either alone or in combination with known diuretics or saluretics or pharmaceutically acceptable carrier is administered to induce increased flow of urine and electrolyte excretion with minimal side effects.

Diuretics are important pharmaceuticals and are used extensively to augment the output of waste fluids and thereby to produce a significant loss of body weight, to reduce or eliminate edema or other symptoms usually associated with hypertension and the retention of an excessive amount of sodium ions in the body.

The classical diuretics, mercurials and xanthines have become restricted in use because it is now recognized that they are toxic upon acute or chronic administration. These compounds also cause side effects such as local inflammation, ecchymosis and plasma electrolyte imbalance.

In recent years, newer diuretics such as the substituted quinazolinones, acetazolamide, chlorothiazide, hydrochlorothiazide, have come into use. While such compounds do not have the side effects of the earlier diuretics, they do have disadvantages such as causing hypokalemia, hyperuricemia and metabolic acidosis. These disturbances of electrolyte balance are undesirable because they can result in listlessness, weakness, apathy and cardiac malfunction.

Another disadvantage of many of the diuretics currently in use is that they do not produce an increase in glomerular filtration rate or increase renal plasma flow as indicated by creatinine and para-amino-hippuric acid clearance rates, standard tests as described in *Principles of Renal Physiology*, Homer W. Smith (1956), New York: Oxford University Press, whereas both actions are desirable for fast, effective reduction in the quantities of water and salt which may be retained in the body tissues.

Now it has been discovered that compounds of the general formula

wherein R₁ represents a member selected from the group consisting of hydrogen, sodium, potassium, or other pharmacologically acceptable cation; R₂ represents a member selected from the group consisting of hydrogen, an alkyl radical having up to 3 carbon atoms, i.e., methyl, ethyl and n-propyl, isopropyl radicals, halogen radicals, phenyl radical, substituted phenyl radical and carboxyl radical;

2

R₃ represents a member selected from the group consisting of hydrogen, halogen radical, an alkoxy radical containing 1 to 3 carbon atoms and an acyloxy group containing 2 to 6 carbon atoms; R₄ represents a member selected from the group consisting of hydrogen, an alkyl radical containing 1 to 3 carbon atoms, an acyl radical selected from the group having 1 to 4 carbon atoms in the alkyl or alkene portion thereof; and R₅ represents a member selected from the group consisting of hydrogen, halogen radical, nitro radical and an alkoxy radical containing 1 to 3 carbon atoms; R₅ being halogen or nitro only when the R₄ substituent is hydrogen, are effective non-toxic diuretics capable of inducing an increase in both glomerular filtration rate and renal plasma flow and may be administered alone or in combination with a pharmaceutically acceptable carrier, the proportions of which are determined by the solubility and chemical nature of the compound, the chosen route of administration, etc., to induce or promote diuresis in mammals without producing undesirable side effects and without loss of effectiveness upon prolonged administration.

Representative compounds useful for the purposes of this invention and falling within the generic structural formula indicated above are the free acids and water-soluble salts of nuclear substituted cinnamic acid, such as 3-methoxy-4-propionoxy cinnamic acid, 4-hydroxy-3-methoxy-5-chloro cinnamic acid, 4-hydroxy-3-methoxy-5-nitro cinnamic acid, 3-methoxy-4-acetoxy cinnamic acid, 3-ethoxy-4-acetoxy cinnamic acid, 3,5-dimethoxy-4-acetoxy cinnamic acid, 3-methoxy-4-n-butyryloxy cinnamic acid, 4-hydroxy cinnamic acid, 3-methoxy-4-hydroxy-5-iodo cinnamic acid, 3-methoxy-4-ethoxy potassium cinnamate, 3-methoxy-4-acetoxy-alpha-methyl cinnamic acid, 4-acetoxy cinnamic acid, 3-methoxy-4-crotonyloxy-benzylidene malonic acid, 3-methoxy-4-isobutyryloxy cinnamic acid, 4-hydroxy-3-methoxy cinnamic acid and the substituted cinnamic acid compounds having a substituent in the acrylic acid portion of said compounds, such as alpha-methyl, alpha-bromo and alpha-(p-nitrophenyl) (cis and trans).

The preferred groups of compounds for use as diuretics are the 3-alkoxy-4-acyloxy cinnamic acids, of which compound 3-methoxy-4-propionoxy (propionyloxy) cinnamic acid is a specific example believed to be a new compound.

In administering the compounds capable of inducing increased urine flow, such compounds may be administered orally in the form of tablets or capsules, which forms may have water soluble coatings such as the synthetic gum carboxymethylcellulose, gelatin, and the like, and may contain starch, milk sugar, etc., as diluents. They may be administered sublingually in the form of soluble troches, etc. They may also be administered parenterally, that is intramuscularly, intravenously, or subcutaneously. For parenteral administration, the compounds may be used in the form of a sterile solution containing other solutes, for example, enough saline or glucose to make the solution isotonic, or in solution, suspension or emulsion in liquid carriers.

The following examples are given by way of illustration and are not to be construed as limitations upon the invention as may variations are possible without departing from the scope and the spirit thereof.

Example I

3-methoxy-4-propionoxy cinnamic acid may be prepared by acylation of ferulic acid with propionic anhydride. Ferulic acid may be prepared by the procedure of Vorsatz as described by J. W. Johnson in *Organic Reactions*, Vol. I, New York: John Wiley & Sons, Inc., 1960, Chap. 8, page 250. In order to obtain good yields of

ferulic acid by this method, it is necessary to have the reactants, i.e., vanillin and malonic acid present in the mole ratio of 1:2.2. In preparing ferulic acid, a closable container is provided with a stopper carrying a calcium chloride guard tube. 2.52 kilograms of vanillin, 3.8 kilograms of malonic acid, 0.17 kilogram of piperidine and 8.3 liters of pyridine are introduced into the container. The mixture is stored for three weeks in a dark place protected from light. The liquid contents of the container are then poured with stirring into 8 liters of precooled, concentrated hydrochloric acid containing 20 pounds of crushed ice. Ferulic acid precipitates immediately. The precipitate is filtered from the acid solution and the recovered solids are washed with 15 liters of 5% hydrochloric acid. The filter cake is then washed with distilled water until the filtrate has a pH of approximately 7. The product obtained upon drying the washed filter cake is relatively pure ferulic acid, M.P. 170° to 172° C. The yield of ferulic acid is approximately 75%.

For the preparation of 3-methoxy-4-propionoxy cinnamic acid, the dried ferulic acid is heated under reflux with an excess of propionic anhydride in the presence of dry pyridine and with suitable mechanical stirring. 388 grams of dried ferulic acid and 1430 grams of propionic anhydride, in a mole ratio of 1:5.5, are introduced into a vessel containing 160 milliliters of dry pyridine and provided with a reflux condenser and a mechanical stirrer. The mixture is heated under reflux for 6 to 10 hours with the internal temperature being maintained in the range of 90° C. to 100° C. The warm mixture is poured into 2 liters of water containing 2 pounds of crushed ice. Initially, the product separates into a dark brown oil, which upon standing from 4 to 6 hours is converted to a white solid. The white solid is separated from aqueous medium by centrifuging. The cake is then washed with water and filtered. Washing of the product is continued until the product is free from any propionic acid. The product is then dried under vacuum at a temperature not exceeding 85° C.

The dried product is purified by fractional crystallization from dilute acetone. For this purpose, the dried product is dissolved in acetone in a weight ratio of approximately 1:20. The solution is mixed with charcoal and filter aids and filtered. The filtrate is concentrated on steam bath to a solution of weight ratio of approximately 1:13, and while warm, the concentrate is diluted with enough water to provide a weight ratio of solids to acetone-water solvent of approximately 1:21. The resulting solution is heated until it just reaches boiling stage and then allowed to cool down to room temperature. It is then stored for 2 to 4 hours in a cold place (about 5° C.). Crystallization occurs slowly. The first crystallize, which is approximately 5% of the total yield, is removed by filtration as it generally contains a product having a melting point in the range of 215° to 220° C. After the separation of first crystallize, the filtrate is warmed on a steam bath until it turns just milky and then is allowed to remain at room temperature for about 4 hours. After storing for 2 hours in a cold room (about 5° C.) a second crystallization occurs. The second crystallize harvested from the dilute acetone solution is pure 3-methoxy-4-propionoxy cinnamic acid, M.P. 156° to 158° C. and shows a single spot in thin layer chromatography. The yield is approximately 85%.

Example II

12 parts of ferulic acid, prepared according to the method described in Example I, are reacted with 50 parts of acetic anhydride and 3 parts of dry pyridine in accordance with the procedure described in Example I for the preparation of 3-methoxy-4-propionoxy cinnamic acid. The reaction product is 3-methoxy-4-acetoxy cinnamic acid, M.P. 192° to 195° C. Upon recrystallization from ethanol, the reaction product is obtained as a white crystalline product, M.P. 202° to 203.5° C.

5.5 parts by weight of 3-methoxy-4-acetoxy cinnamic

acid are suspended in 20 parts of methanol and are titrated with a 5% aqueous solution of potassium hydroxide using a glass electrode until a pH of 8.3 is indicated. A pale yellow precipitate is separated by filtration. The filtrate is concentrated under an atmosphere of nitrogen, to a thick syrup. The syrup is brought into solution using methanol. Diethyl ether is added dropwise to the methanolic solution to achieve a faint turbidity. The cloudy solution is set aside in a cold place for crystallization. The crystalline product harvested is the potassium salt of 3-methoxy-4-acetoxy cinnamic acid, yellow in color and hygroscopic. It should preferably be stored in a closed container in a cold place, protected from light.

Example III

4-hydroxy-3-methoxy-5-chloro cinnamic acid is prepared by Vorsatz's method, described under Example I for the preparation of ferulic acid. The required aldehyde, 5-chloro vanillin is prepared by passing chlorine into a solution of vanillin and chloroform.

37.3 grams (0.2 mole) of 5-chloro vanillin, crystallized from ethanol, M.P. 166° to 167° C., 45.75 grams (0.44 mole) of malonic acid, 120 milliliters of pyridine and 3 milliliters of piperidine are kept for three weeks at room temperature (20° C.), protected from light in a closed container provided with a calcium chloride guard tube. Then the liquid contents are poured into 120 milliliters of cold concentrated hydrochloric acid. The 4-hydroxy-3-methoxy-5-chloro cinnamic acid precipitates from the solution. The precipitate is filtered, washed with a liter of 3% hydrochloric acid and cold water until neutral to litmus. The precipitate is dried in vacuum at a temperature not exceeding 85° C. The dried material crystallizes from dilute ethanol as glistening pale yellow needles, M.P. 245° to 246° C.

Example IV

12 parts of vanillin, 7 parts of p-nitrophenylacetic acid, 4 parts of pyridine and 40 parts of acetic anhydride are heated under reflux at approximately 150° C. bath temperature for 30 minutes. The reaction mixture is poured into 8 parts of cold concentrated hydrochloric acid with stirring. A yellow precipitate is formed after standing for ten minutes. The precipitate is dissolved in an excess of benzene, 550 parts. The benzene solution is washed twice with water, 300 parts for each washing, and the layers separated. The aqueous washings are discarded. The benzene solution is then extracted with 0.2% solution of caustic soda, four times in succession, with 300 parts per each extraction. The benzene solution is next washed twice with 250 parts of water. The latter aqueous washings are combined with the dilute alkaline extracts of the benzene solution.

The combined alkaline solutions are first acidified to pH 4.0 with acetic acid. A yellow precipitate separates and is collected by filtration. The precipitate is alpha-p-nitrophenyl - trans-3-methoxy-4-acetoxy cinnamic acid, M.P. 195° to 197° C., obtained in a yield of 6.7 parts. It crystallizes from hot ethyl acetate as yellow needles, M.P. 205° to 207° C.

The filtrates at pH 4, separated from the trans compound described above, and next acidified to pH 1.8 by the addition of concentrated hydrochloric acid. Now, an orange precipitate is obtained, M.P. 125° C., which is the cis compound, viz, alpha-p-nitrophenyl-cis-3-methoxy-4-acetoxy cinnamic acid; yield 1 part.

Evaluation of the product of Example I as a diuretic was made by the following test on a female dog of 8.0 kg. body weight.

The trained unanesthetized dog was placed in a comfortable position on a padded board and lightly restrained. A self-retaining Foley catheter was passed per urethra into the bladder, the residual urine evacuated, and the catheter left in situ.

20 ml./kg. body weight of a solution containing 2.5%

by weight of dextrose in physiological saline was given by gastric tube to provide a fluid load.

A forelimb vein was entered by means of an 18T gauge needle. A polyethylene venous infusion catheter was then passed into the vein through the needle, the needle being subsequently withdrawn and the catheter kept in place by means of adhesive strapping. A constant infusion of approximately 30 to 35 ml./hour dextrose-saline was maintained throughout the experimental period.

Urine was collected every hour for 3 hours. 25 mg./kg. 3-methoxy-4-propionoxy cinnamic acid was administered by mouth in capsule form. Urine was collected every hour thereafter for 3 hours. Urine samples were analyzed for sodium, potassium, chloride and bicarbonate levels. The following analysis shows the amount of sodium, potassium, chloride and bicarbonate in the urine before and after use of the product of Example I.

TABLE I

Hours	Electrolyte Excretion (μeq./min.)				Urine Flow (ml./min.)
	Na ⁺	K ⁺	Cl ⁻	HCO ₃ ⁻	
1-----	49.1	10.6	61.9	1.10	1.07
2-----	46.2	6.53	42.5	1.40	0.47
3-----	81.0	5.40	84.6	1.35	0.45
Medication—25 mg./kg. oral capsule product of Example I					
4-----	144.4	14.3	156.7	10.5	0.95
5-----	107.8	25.6	113.9	17.7	0.89
6-----	130.8	22.7	114.4	23.5	0.78
1-----	46.4	30.3	42.9	21.7	0.43
2-----	58.8	14.9	33.1	21.9	0.47
Medication—25 mg./kg. oral capsule product of Example I					
3-----	65.3	8.0	42.7	14.7	0.67
4-----	109.3	16.1	104.5	9.5	0.95

Evaluation of the product of Example II as a diuretic was made by the following test on a cat of 2.46 kilograms body weight. The cat was nembutal anesthetized and the bladder and the femoral veins cannulated. An infusion was made to produce a saline load of 20 ml. per kilogram of weight. The product of Example II was dissolved in water and injected intravenously. Thereafter saline was added in amounts to continuously balance the urine output.

The result of testing the product of Example II is given in Table II and the analysis of the electrolyte excretion, μeq./min. is given in Table III.

TABLE II

Period	Urine Flow (ml./hr.)	Urine Flow (ml./kg.)	Urine Flow Ratio
Control	3.5	1.42	1.00
Hour 1	5 mg./kg.	1.34	0.94
Hour 2	5 mg./kg.	2.84	2.00
Hour 3	5 mg./kg.	8.13	5.75
Hour 4	5 mg./kg.	14.4	10.1
Hour 5	5 mg./kg.	14.6	10.3
Hour 6	5 mg./kg.	14.2	10.0

TABLE III

Period	Electrolyte Excretion (μeq./min.)			
	Na ⁺	K ⁺	Cl ⁻	HCO ₃ ⁻
Hour 1	11.2	6.15	7.75	0.15
Hour 2	15.5	8.05	19.7	0.33
Hour 3	22.3	9.0	27.0	0.67
Hour 4	66.7	10.6	63.3	3.5
Hour 5	67.6	10.0	71.5	7.2
Hour 6	72.3	8.75	56.0	4.1

Evaluation of the product of Example III as a diuretic was made by the following test on a cat of 2.15 kilograms body weight. The cat was nembutal anesthetized and the bladder and the femoral veins cannulated. An infusion was made to produce a saline load of 30 ml. per kilogram of weight. The product of Example III was suspended in oil and administered intramuscularly. Thereafter saline was added in amounts to continuously balance the urine output.

The result of testing the product of Example III is given in Table IV.

TABLE IV

Period	Urine Flow (ml./hr.)	Urine Flow (ml./kg.)	Urine Flow Ratio
Control	2.5	1.16	1.00
25 mg./kg. product of Example III			
Hour 1	8.0	3.72	3.21
Hour 2	12.0	5.58	4.81
Hour 3	16.5	7.67	6.62
Hour 4	13.0	6.50	5.21
Hour 5	19.0	8.84	7.61
Hour 6	24.5	11.40	9.83

The product of Example IV was tested with Holtzman male rats. The rats were tested in groups of four. An infusion was made to produce a saline load of 20 ml. per kilogram of weight. The product of Example IV was suspended in oil and administered intramuscularly.

The result of testing the product of Example IV is given in Table V.

TABLE V

Period	Urine Volume/5 hrs. (ml.)	Urine Flow Ratio (ml./100 g./5 hrs.)
Control Group A	0.5	1.4
Control Group B	11.5	1.7
Test Group	20.0	2.9

I claim:

1. The method of promoting diuresis in animals which comprises administering pharmacologically active dosages of a compound selected from the group having the general formula

wherein R₁ represents a member selected from the group consisting of hydrogen, sodium and potassium; R₂ represents a member selected from the group consisting of hydrogen, alkyl radicals having up to 3 carbon atoms, halogen radicals, the phenyl radical, nitro substituted phenyl radicals, and the carboxyl radical; R₃ represents a member selected from the group consisting of hydrogen, halogen radicals and alkoxy radicals containing 1 to 3 carbon atoms; R₄ represents a member selected from the group consisting of hydrogen, alkyl radicals containing 1 to 3 carbon atoms, acyl radicals selected from the group having 1 to 4 carbon atoms in the hydrocarbon portion thereof; and R₅ represents a member selected from the group consisting of hydrogen, halogen radicals, and alkoxy radicals containing 1 to 3 carbon atoms; R₅ being halogen only when the R₄ substituent is hydrogen.

2. The method of promoting diuresis in animals which comprises administering pharmacologically active dosages of a nuclear substituted cinnamic acid wherein the nuclear substituents are hydroxyl in the 4 position, alkoxy

in the 3 position, and halogen in the 5 position, said alkoxy group containing 1 to 3 carbon atoms.

3. The method of promoting diuresis in animals which comprises administering pharmacologically active dosages of 4 hydroxy-3-methoxy-5-chloro cinnamic acid.

4. An article comprising a water soluble coating composition enclosing a powdered compound of the general formula

wherein R₁ represents a member selected from the group consisting of hydrogen, sodium and potassium; R₂ represents a member selected from the group consisting of hydrogen, alkyl radicals having up to 3 carbon atoms, halo-

gen radicals, the phenyl radical, nitro substituted phenyl radical, and carboxyl radicals, R₃ represents a member selected from the group consisting of hydrogen, halogen radicals, and carboxyl radicals, R₃ represents a member atoms; R₄ represents a member selected from the group consisting of hydrogen, alkyl radicals containing 1 to 3 carbon atoms, acyl radicals, selected from the group having 1 to 4 carbon atoms in the hydrocarbon portion thereof; and R₅ represents a member selected from the group consisting of hydrogen, halogen radicals, and alkoxyl radicals containing 1 to 3 carbon atoms; R₅ being halogen only when the R₄ substituent is hydrogen.
